(57) CLAIM

The ornamental design for interchangeable shoe, as shown and described.

DESCRIPTION

FIG. 1 is a perspective view of the interchangeable shoe showing my new design;

FIG. 2 is a perspective exploded view thereof;

FIG. 3 is another perspective exploded view thereof;

FIG. 4 is a right side elevation view thereof;

FIG. 5 is a left side elevation view thereof;

FIG. 6 is a front side elevation view thereof;

FIG. 7 is a back side elevation view thereof; and,

FIG. 8 is a right side elevation view thereof.

The broken lines in the drawings depict parts of the interchangeable shoe that form no part of the claimed design.
